UNITED STATES PATENT OFFICE.

JAMES A. ROSS, OF CHICAGO, ILLINOIS.

STEAM-BOILER.

No. 819,601.

Specification of Letters Patent.

Patented May 1, 1906.

Application filed October 20, 1905. Serial No. 283,630.

To all whom it may concern:

Be it known that I, JAMES A. ROSS, a citizen of the United States, residing at Chicago, in the county of Cook and State of Illinois, 5 have invented new and useful Improvements in Steam-Boilers, of which the following is a specification.

This invention relates to steam-boilers, and has for its object to provide a better boiler 10 than heretofore, one which will generate a greater amount of steam from a given amount of fuel.

A further object of the invention is to so construct the boiler that the flames and furnace-gases will travel a long course through 15 the boiler, whereby a large boiler-surface is exposed to the heat and the thorough and complete combustion of the fuel is attained.

These objects are effected by the construction shown in the accompanying drawings, 20 in which—

Figure 1 is a front elevation of the boiler, and Fig. 2 is a central longitudinal section.

The boiler is a combination of the "wagon" 25 and "water-tube" types, consisting of a shell of the wagon type having an upper chamber and steam-space and legs on each side, which incloses the fireplace, and two banks of water-tubes which extend lengthwise across the 30 combustion-chamber and are separated by a baffle-partition, so that the flames pass to the back of the furnace along the lower bank and return to the stack along the upper bank.

Referring specifically to the drawings, 35 indicates the upper steam dome or chamber formed by the outer and inner casings 7 and 8 and having legs 9 at each side, which inclose the fireplace and combustion-chamber. Water-legs or hollow water-containing walls 40 are also produced at the front and rear ends of the boiler, as indicated at 10 and 11. It will be seen that the shell so formed is of the wagon type and surrounds on all sides the fire-box and the combustion-chamber.

45 The grate is indicated at 12 and the door thereto at 13, the bridge-wall at 14, and the outlet to the stack at 15. Extending lengthwise of the combustion-chamber within the inner shell 8 is a baffle-partition 16, which 50 extends from the front of the boiler to near the rear end thereof.

At 17 and 18 are indicated, respectively, lower and upper banks of water-tubes. The lower bank extends from a header 18^a, located at the rear wall of the boiler, to the lower section 19 of a header supported in the

front wall of the boiler. The tubes incline upwardly from the rear header to the front header, and the former is connected to the rear leg 11 of the boiler by a pipe 20. The 60 bank 18 inclines upwardly from the upper section 21 of the front header to a rear header 22, which is connected by a pipe 23 with the steam-dome or upper space 6 of the boiler. The sections 19 and 21 are connected by a 65 passage 24. The flanges which produce this passage give additional strength or rigidity to the header. A cover 25 closes the opening in the rear wall of the boiler between the headers 18^a and 22. This cover can be removed when desired to get at the interior of the boiler.

The flames from the fire pass back along the bank of tubes 17 and then around the end of the baffle 16 and forwardly along the bank 75 18 to the stack 15. The feed-water, which is preferably admitted into one of the legs 9, flows up through the pipe 20 into the header 18^a, and thence along through the bank 17 to the headers 19 and 21, and thence through 80 the bank 18 to the header 22, and up the pipe 23 to the steam-dome 6. It will be seen that the water gets the benefit of the fire during its course through the banks and also while in the outer shell or casing, so that a high 85 degree of efficiency is produced, and the long travel of the gases through the combustion-chamber gives time for the smoke and other products of combustion to be consumed.

What I claim as new, and desire to secure 90 by Letters Patent, is—

1. A boiler comprising an upper dome and hollow walls or legs depending therefrom around the combustion-chamber, a front header set in the front wall, upper and lower 95 rear headers set in the rear wall and having connecting-pipes therewith, and upper and lower banks of water-tubes connecting the front header and the respective rear headers.

2. A boiler of the wagon type, comprising 100 an upper chamber or dome and legs or hollow walls formed of spaced casings and surrounding the combustion-chamber and having an outlet to the stack extending upwardly through the casings and the dome, at 105 the front thereof, a header supported in the front wall and upper and lower headers supported in the rear wall, a bank of tubes inclined upwardly from the lower rear header to the front header, another bank inclined 110 upwardly from the front header to the upper rear header, connections from the rear head-

ers into the body of the boiler, and a baffle
extending rearwardly from the front wall,
across the combustion-chamber and between
said bank of tubes, and causing a flow of the
products of combustion rearwardly along the
lower bank and forwardly along the upper
bank to the outlet.

In testimony whereof I have signed my
name to this specification in the presence of
two subscribing witnesses.

JAMES A. ROSS.
